McDOWELL DARROW, OF ROCHESTER, NEW YORK.

Letters Patent No. 66,952, dated July 23, 1867.

IMPROVED APPARATUS FOR HEATING TIRES.

The Schedule referred to in these Letters Patent and making part of the same.

TO ALL WHOM IT MAY CONCERN:

Be it known that I, McDOWELL DARROW, of Rochester, in the county of Monroe, and State of New York, have invented a certain new and useful improvement in Tire-Heaters; and I do hereby declare that the following is a full and exact description thereof, reference being had to the accompanying drawings, making part of this specification.

Figure 1 is a plan of my improved heater with a portion of the cover broken away to show the interior arrangement.

Figure 2 is an elevation thereof.

Figure 3 is a vertical section.

Like letters of reference indicate corresponding parts in all the figures.

This arrangement is intended for heating tires to apply to wheels. The invention consists in an annular heating-chamber, formed in compartments whose partitions extend part way up, the effect being to equalize the burning of the fuel around the tire, but at the same time allow the necessary draught; and furthermore, in connection therewith, the employment of registers over the compartments, for the admission of air to further equalize the combustion and the heating of the tire.

As represented in the drawings, A is an annular chamber of sufficient size to receive ordinary tires of different diameters; and B is a removable cover that fits closely over it. The draught is admitted through doors at a, and discharges through smoke pipe at b. The interior of the chamber is divided into a series of compartments, c c, by partitions d d, which, however, extend but part way up, and serve to support the tire thereon as it is being heated. Over the compartments is a series of registers, f f, in the cover.

The charcoal or other fuel is placed in the compartments, around the tire, and ignited. Were it not for the compartments the fire would sweep around from the doors a and burn unequally. The partitions, extending only part way up the height of the chamber, allow the necessary passage for the draught over them, but at the same time obstruct the passage of the fire, and thus produces an equality in the combustion that could not otherwise be obtained.

The employment of the registers f f in the cover also serves to equalize the combustion by allowing cold air to enter at any desired point, and thereby, deaden the burning at that point. They also serve to equalize the heat of the tire by equalizing the combustion. They further serve as peep holes to determine the state of the tire at any time.

What I claim as my invention, and desire to secure by Letters Patent, is—

A tire-heater, having compartments c c, and registers f f, and which is otherwise constructed and arranged as described, and which operates as herein set forth.

In witness whereof I have hereunto signed my name in the presence of two subscribing witnesses.

McDOWELL DARROW.
